Application June 6, 1932, Serial No. 615,592

25 Claims. (Cl. 199—31)

The present invention relates to linecasting and comprising machines and particularly to improvements in automatic control units therefor.

- 5 One of the objects of the present invention is to provide a mechanism effective in the event of interference with the movement of the matrix assembling elevator to absorb harmlessly the power applied thereto.
- 10 Another object of the present invention is to provide a duplex rail mechanism in the matrix assembling block that is controllable automatically and that assumes a set condition during transit whereby displacement or scattering of assembled matrices is prevented.
- 15 The present invention contemplates improvements in automatic control devices such as, for example, the device disclosed in copending application Serial No. 600,606 filed March 23, 1932, 20 and referred to hereinafter as the copending application.

25 For convenience in disclosing the present invention a concise description of the structure of the invention constituting the copending application will be set forth herein, but for a more complete understanding of the details of the structure reference should be had to the cited copending application. However, only such reference is here being made as is believed necessary for a comprehensive presentation of the invention.

30 The present control device admits of a compact and unitary mechanism that is applicable to the keyboard of a standard linecasting and 35 composing machine, which will be referred to generally hereinafter as the principal machine. A plurality of actuators communicate with the individual release mechanisms of a principal machine and are brought into selective operation through the instrumentality of a code bar selector mechanism. The selection of an actuator is accomplished by each of a plurality of permutable positionments of a set of code bars under control of a record reader mechanism.

45 In the preferred practice the record reader mechanism contains a set of feelers functioning to sense the successive transverse conditions of a perforated control form. For each longitudinal track in the control form there is associated one such feeler member which, upon the occurrence or absence of a perforation in a particular position in its track, causes a corresponding movement of its associated permutation or code bar. Power is taken from the

principal machine by a conveniently located power take-off mechanism and is distributed over a pair of shafts, to one of which is delegated the operation of the aforementioned record reader and selector mechanism, while to the other is delegated the operation of the elevator and its associated mechanisms.

5 It has become a widespread commercial practice to provide each matrix with two matrix im- 10 pressions or mold faces usually of the same character, but of different styles of type so that by presenting a matrix in either of two positions one or another of these mold faces may be made to register opposite the molding chamber in the linecasting machine. On being 15 received onto the assembling block, the individual matrices are supported by a pair of side- 20 wardly extending lugs which are integral therewith and which rest upon either of two sets of rails. The upper of the two sets of rails de- 25 termines the position in which the matrices shall be received, since the presentation or withdrawal of the foremost portion of one of said upper sets of rails at the ingress end of the assembling block resolves the entering position of 30 the matrices, after which, the latter progress toward the other end of the block by sliding upon the other of the set and the remainder of that rail upon which it started. In accordance with the present invention it is contem- 35 plated to provide mechanism for presenting or withdrawing the determining rail upon which the relative assembling position of the matrix is dependent under supervision of the control unit and in response to a predetermined signal. 40 In addition to thus operating the rail automatically provision is also made for using it for a matrix lock-up device during such time as the elevator and assembling block are in transit in order that the matrices may be maintained in an orderly alignment while they are carried from the composing position to the casting position.

45 Under manual operation the matrix assembling elevator of the principal machine is actuated by means of a handle secured to the one end of the elevator operating shaft which traverses the foremost portion of the keyboard. The present improvement contemplates a power 50 drive connection through the selfsame operating shaft but since the operation of the elevator is of its nature accompanied by a possible obstruction or interference means are provided for disabling the drive connection by rendering it ineffective without altogether disjoining it. 55

Among the features of this invention which contribute to the aforementioned general objects particularly noteworthy ones reside in providing such a connection which is compact and positive in operation, which permits of adjustment to accommodate individual requirements and one which is almost entirely encased to assure safety to the attendant as well as to be least exposed to dust settlement and foreign deposit.

10 A more complete understanding of the present invention will be had from the following description when taken in conjunction with the accompanying drawings in which

15 Fig. 1 is a plan view of the keyboard of a principal machine with parts broken away, illustrating the application of an automatic control unit embodying the present invention.

20 Fig. 2 is a detailed perspective view of the power distributing mechanism forming part of the control unit with portions omitted to permit of a better illustration of the elevator control handle.

25 Fig. 3 is a detailed sectional view taken approximately on line 3—3 of Fig. 1 featuring the elevator control handle and the resilient connection therein.

30 Fig. 4 is a fragmentary detail view similar to Fig. 3 but illustrating an operated position of the elevator control handle.

35 Fig. 5 is a detailed fragmentary elevational view similar to Figs. 3 and 4 but illustrating another operated position of the elevator control handle.

40 Fig. 6 is a transverse sectional view through the keyboard of the principal machine illustrating the action from the automatic and manual actuators through and including the matrix release mechanism.

45 Fig. 7 is a left side elevation of the principal machine illustrating the elevator raising arm and the duplex rail mechanism.

50 Fig. 8 is a detailed perspective view of a portion of the assembling block illustrating the mode in which the individual matrices are assembled for variously presenting their molding faces into casting position.

55 Fig. 9 is a front elevational view of a portion of a line-casting machine featuring a modified form of assembling block rail shift mechanism.

60 Fig. 10 is a fragmentary side elevational view of a line-casting machine partially in section featuring the modified structure also illustrated in Fig. 9.

65 Fig. 11 is a detail perspective view of the double code shift mechanism adapted for use with the structure illustrated in Fig. 9.

70 Fig. 12 is a fragmentary perspective view of the interior of an assembling block illustrating the application thereto of a rail shift mechanism such as is shown in Fig. 9.

75 Fig. 13 is a fragmentary sectional view generally similar to Fig. 12 but illustrating a shift position of the rail.

80 Particular reference is had to the accompanying drawings in the course of the following detailed description in which like reference characters designate similar parts throughout.

General description

85 As explained in the copending application, power for operating the control unit is obtained from the principal machine by means of a power take-off mechanism constituting generally a shaft 15, Fig. 1, pulley driven from the intermediate shaft of the principal machine. A pair

90 of tributary shafts 16 and 17 are driven from constantly rotating shaft 15 through gears 18 and 19 freely mounted upon their corresponding shafts 16 and 17. Each of these tributary shafts are provided with a spring loaded tooth clutch 21 and 22 and disengagement levers 23 and 24 whereby one or another of the two shafts is brought into operative engagement with its gear 18 or 19 which is constantly driven from the common driving shaft 15.

95 Shaft 16 carries driving means which control and operate a record reader mechanism 25 and gear 26 which imparts motion to the selector mechanism, while shaft 17 carries an elevator operating cam 27 and a special clutch cam 28 the latter of which functions to control a single revolution clutch mechanism (not shown) which subordinates shaft 17. The two clutch control levers 23 and 24 are, as between themselves, intercontrolled, as more fully described in the copending application, whereby neither may be actuated until the other has completed its previous performance.

100 This intercontrol mechanism may be described generally as follows, having particular reference to Figs. 1, 2 and 6: During the operation of the principal machine the major portion of the operative cycle is normally expended in performing composing machine control functions. At the conclusion of a predetermined number of matrix release functions there appears in the control form an elevator actuating code combination of perforations which causes the following response.

105 A definite alignment of notches 29 are presented opposite a selector bar 31 and the latter bar is thrust forwardly in the usual mode of selective operation to be more particularly explained in connection with the selector mechanism hereinafter, engaging with a lug 32 formed integrally therewith one arm 33 of a T-lever 34 pivotally mounted at 35, rotating the latter counterclockwise and against the tendencies of a spring 36 which normally urges it in an opposite direction, Figs. 1 and 2. Another arm 37 of lever 34 has pivotally connected to it a bar 38 the remote end of which is offset and has a shoulder 39 adapted for cooperation with a corresponding shoulder 41 of a spring actuated latch lever 42. The other arm 43 of lever 34 is connected to a link 44 which in turn is articulated to clutch release lever 23 of the record reader shaft 16 so as to pull it positively into effective position for disengaging clutch 21 but with loose joint connection in the other direction in which a spring (not shown) functions to return it.

110 Thus it will be understood that upon being selected bar 31 rotates T-lever 34 counterclockwise causing it to be latched by lever 42 and holding disengagement lever 23 in its effective position. Bar 33, by being connected to one end of a floating lever 45, causes the latter to collide with one arm 46 of a bellcrank 47, the other arm 48 of which normally blocks clutch 65 disengagement lever 24 of elevator shaft 17, holding it in effective position, but upon the movement of bar 33 bellcrank 47 is allowed to be moved out of effective position permitting clutch 22 to become engaged and imparting motion to the elevator cam shaft 17.

115 Cam shaft 17 proceeds through one revolution, coming to rest under control of a single revolution mechanism associated with its clutch 22, but during its cycle a cam 49 carried upon

it acts upon latch 42 to release bar 38 and restore T-lever 34 to normal position. Clutch lever 23, however, is not necessarily restored with it until the complete descent of the elevator, operating through a finger 51, which (to be completely described later) withdraws arm 52 of cradle 53 from blocking lever 23.

Control

10 A control form 54 is previously prepared in a keyboard perforating mechanism such as, for example, the one illustrated and described in copending application Serial No. 601,172 filed March 25, 1932 after which it is threaded through the receiving die 55 of a record reader mechanism generally indicated 25. In progressing through the reader mechanism each transverse row of perforations in the form 54 is simultaneously sensed by a set of feeler levers 56 and, in accordance with the setting thereof as received from the control form, a corresponding set of transfer levers 57 is also positioned and in turn imparts the setting to a corresponding set of code bars 58 through the medium of 20 individual connecting rods 59. The tape 54 is fed intermittently through the record reader mechanism 25 preferably by pawl and ratchet engagement (not shown) and is permitted a sufficient rest interval intervening said motions 25 during which to transfer the reading or setting to the set of code bars 58 as just described.

Code bars 58, as best seen in Fig. 2, are provided with variously spaced notches 29 so distributed that upon each permutative positionment thereof one and only one transverse alignment of notches 29 is afforded. Alternately and oppositely disposed adjacent said code bars 58 are a double alignment of selectable bars 61 as well as the elevator selector bar 31 all of 40 which are individually spring urged to engage the several code bars 58 and generally prevented from further movement by the interposition of lugs 62 of one or more of the several code bars 58. In accordance with each positionment of the several code bars, one of the selectable bars 61 or 31 is afforded a clearance by the alignment of notches 29 aforementioned and is permitted to enter into said alignment and to assume a position substantially as that illustrated 45 in dotted lines in Fig. 6 and hereinafter to be referred to as the selected position.

Immediately upon assuming selected position a particular bar 61 is driven rightwardly, as viewed in Fig. 6, under the influence of a common actuator bar 63 which in turn receives its motion from a pair of concurrently operating cams 64 secured to and rotatable with a spreader cam shaft 65 and located at the opposite ends thereof. In its movement rightwardly bar 61 through its foremost portion collides with a depending arm 66 of a bellcrank member 67, displaceably fulcrumed in alignment on a common shaft 68 with a plurality of other and similar bellcranks, each of which is associated with a corresponding keylever 69.

65 The contour of actuator cams 64, as may be seen from Fig. 6, is such that an abrupt and measured blow is imparted to the common actuator 63 which through bellcranks 67 operates to impart a corresponding blow to keylevers 69. This blow or "touch" may be developed to such critical characteristics in accordance with the proposed structure as to simulate the release stroke usually delivered by an experienced operator and serves 70 to raise weights 71 sufficiently to cause the ar-

ticulated triggers 72 of timed release mechanisms 73 to disengage their respective yokes 14.

The mechanism from this point of operation, where the matrices are released until an instant shortly before they are received upon the assembling block 75, is well known and is sufficiently described in the copending application referred to so as not to be necessary to a clear understanding of the present invention.

10

Rail shift

As the several matrices and space bands are released from their respective magazines they precipitate onto a conveyor belt and are carried into position on an assembling block 75, Fig. 8. 15 As mentioned above, block 75 is provided with two sets of rails, the lowermost set of which 76 is permanent and preferably integrally formed with the block 75, while the upper one 77 is comprised of two abutting sections on the forward 20 or right-hand side as viewed in Fig. 7, and a single integral section on the left-hand side. Portion 78 of right-hand rail 77 is movable on block 75 and in accordance with its presentment or withdrawal, being in the foremost portion, determines the receiving position of subsequently released matrices. The rearmost section 79 (Fig. 8) may also be made withdrawable but need not be so since its relative position is not directly material towards determining the positioning of 30 the received matrices, for once they are supported by one or the other of the two sets of rails 76 or 77 their movement during assembly causes them merely to slide onwardly upon whichever rail they are positioned. Through the 35 upper position in the assembling block is maintained upon a pair of rails one of which is constituted by the movable section 78 described above it will be understood that satisfactory results may be had with the use of but one rail, 40 (the right-hand one) and that the inert left-hand rail serves, merely, to balance the support of the assembled matrices. Where a pair of rails are used as in the illustration the foremost or ingress end of the inert rail is removed so as to 45 permit of the selective positionment of assembled matrices described, but where no inert rail 77 is used a further advantage may be had by the use of a rail 78 that is removable throughout its entire length. After a line of matrices is 50 assembled having some matrices in the upper position and some in the lower or where all of the matrices are assembled in the upper position and where thereafter it becomes desirable to change the line so as to have the entire line in 55 the lower position with a structure such as the last mentioned it is necessary but to withdraw the entire rail and allow all of the matrices to fall to the lower position.

One phase of the present invention resides in 60 providing the means about to be described whereby the foremost portion 78 of the movable rail may be automatically presented or withdrawn under control of the selector mechanism of the control unit and thereby function in response to perforated signals in the control form.

In the preferred practice of the present invention the foremost portion 78, Fig. 7, of the removable rail has articulated to it one arm 83 of a T-lever 84 which is pivoted at 82. Arm 83 70 as well as the one 84 opposite to it each carry an adjustment screw 85 for determining and adjusting the limit of motion of lever 84 while a third arm 86 is pivotally connected to a link 87 the opposite terminal of which is in turn pivoted 75

to one end of a first class lever 88. Lever 88 is normally spring urged clockwise as illustrated in Fig. 7 and is provided at the opposite end with a shoulder 89. A release lever 91 pivoted at 92 is equipped with a cooperating shoulder 93 normally adapted by engagement with the first mentioned shoulder 89 to maintain lever 88 in its extreme counterclockwise position whereat rail 78 is withheld as illustrated in solid lines. 10 Upon being released, either manually through its upper end 94 or automatically through its lower end 95, release lever 91 is rotated clockwise until its shoulder 93 failing to withhold lever 88 against the influence of its spring 96 causes 15 thereby the presentation of rail 78 into its effective or presented position as illustrated in dotted lines. The automatic release of lever 91 is brought about through the agency of a vertically pivoted bar 100 one end of which is provided 20 with a screw 110 whereby its stroke may be adjusted and through which it engages the lower extremity 95 of lever 91. The other end of lever 100 is disposed in the path of a lug similar in all particulars to lug 32 of elevator selector bar 25 81 and is acted upon by the former in the same manner under control of a special signal.

It will be understood that in accordance with this form of the present invention a portion of an assembled line may be constituted of lower rail characters while the remainder of the line may be constituted of upper rail characters or the entire line may consist of either types of characters. On account of the variation in thickness between some of the thin matrices and 30 the relatively thick ones, and in the absence of any provision for moving the newly assembled matrices well forward upon the block 75 as soon as they are received, the laterally shiftable rail of Figs. 7 and 10 may not function in the assembling of mixed upper level and lower level matrices under solely automatic control. This is true because the cutaway portion of the inert left-hand rail 71 if made large enough to permit the thickest matrix sufficient clearance so that it 35 may drop to the lower level when the shiftable section 78 is withdrawn, will be too great to afford the thin matrices any support which are last to be received in the upper or bold position and which are immediately followed by a rail 40 shift operation intended to affect only the following received matrices. For this reason the laterally shiftable rail is best adapted to solid line bold or roman composition and not to mixed composition for which purpose the longitudinal- 45 ly shiftable rail of Fig. 9 is better suited.

Lever 88 is carried upon a lifting arm 97 which is secured to the left end of elevator shaft 98 as viewed in Fig. 1 and has appurtenant to it a downwardly extending lug 99, Fig. 7, to which 50 is fastened one end of an expandable spring 101 the other end of which is conveniently secured to a part of the framework. The extremity of arm 97 is pivotally connected to elevator 102 by a link 103 through which it is pushed upwardly 55 during the oscillation of shaft 98. Since lever 88 being pivotally supported by arm 97 must accordingly move with it, its shoulder 89 is freed from engagement with release lever 91 during 60 operation of the elevator raising mechanism and 65 under influence of spring 96 it is caused to rotate clockwise moving rail 78 into the presented position as distinguished from the other or withdrawn position. Thus it will be understood that 70 during the operation of the elevator, rail 78 is invariably presented in supporting position 75

whereat the latter overlies the lugs 104 of those matrices which are positioned on the lower rail 78 and locks them in so that after the upward movement of the elevator the sudden stop thereof will not dislodge them.

In descending, after having delivered its load of matrices, elevator 102 and its associated elements move from the dotted line position, as illustrated in Fig. 7, to the solid line position, and in so doing lever 88 carried by lifting arm 97 10 reengages with its shouldered portion 89 the cooperating shoulder 93 of release lever 91, automatically restoring thereby the movable rail 78 to its withdrawn position in preparation for a subsequent composing operation. It will be understood, therefore, that the normal position of the shiftable rail corresponds to the one illustrated in solid lines, while the alternative or operated position corresponds to the one illustrated in dotted lines.

5

15

20

Elevator disabling mechanism

At the right end of elevator shaft 98, Fig. 1, there is secured a manual operating handle 105 having associated therewith an auxiliary portion 106 operating independently as a crank arm and freely supported on shaft 98 as also illustrated in Figs. 3 to 5. The foremost extremity of auxiliary portion 106 carries a follower roller 107 normally adapted to rest upon cam 27 of elevator cam shaft 17, while the rearward portion terminates with an arcuate segment 109, eccentric with respect to elevator shaft 98 and varying therewith, but having a major radius at about point 111 which gradually diminishes towards a minor radius at about point 112. In cooperation with this arcuate portion 109 a roller 113 carried foremost on a plunger 114 is constantly urged by a compression spring 115 housed within the handle 105. The force applied to plunger 114 by spring 115 may be varied by turning adjustment screw 116 located at the heel portion of handle 105. This adjustment screw 116 includes a bushing 117 through which extends the head portion 118 of screw 116 and 30 against which a flange 119 thereof constantly is abutted. A sleeve 121 is threaded upon screw 116 and engages with its foremost portion the rear end of spring 115. By rotating adjustment screw 116 in one direction or the other, sleeve 121 is 35 moved longitudinally thereon and is caused to compress or expand spring 115.

40

45

50

55

60

65

70

75

Auxiliary portion or crank arm 106 has integrally formed therewith a sidewardly extending lug 122 best seen in Fig. 1. A screw 123 threaded through lug 122 is adapted to engage a cooperating lug 124 formed integrally with the hub portion 125 of handle 105 so that in the counterclockwise movement of handle 105 as viewed in Fig. 5 the engagement between the lug 124 and the screw 123 of lug 122 positively imparts similar motion to auxiliary member 106, though a counterclockwise motion originating with auxiliary member 106 does not impart a corresponding motion positively to handle 105 but only a yieldable force which moves handle 105 in the absence of sufficient resistance to its movement for causing the compression of spring 115 by action of segment 109 against roller 113. Be it understood that in the event of any interference with the rotation of shaft 98 either through the blocking of handle 105 or a blocking of the elevator 102 the force imparted from driven shaft 17 through cam 27 to auxiliary member 106 is dissipated in compressing spring 115 and 75

is ineffective beyond the auxiliary member 106, while, on the other hand when cam 27 returns, arm 106 follows therewith through the action of spring 115 and roller 113 upon surface 111 in seeking to intercept a minimum radius between itself and pivot 98.

A lever 126 pivotally carried upon shaft 98 is provided at its foremost portion with an extending finger 51 and at its rearmost portion with an arcuate segment 128. An elongated opening is provided in segment 128 which corresponds to a pair of intersecting circular holes 129 and 131, and into one of which 129 there is normally urged a spring pressed detent 132, Fig. 1. Arcuate segment 128 terminates with a sideward extension 133 subjacent the handle 105, so as to be engaged conveniently by an operator as a finger piece.

Finger 51 during the normal operation of the mechanism is adapted to press upon a cooperating extension 134 of the pivoted cradle member 53, best illustrated in Fig. 2. Cradle member 53 is normally spring urged in a clockwise direction but is constrained from movement in response to its spring 135 by the aforementioned engagement with finger 51. Blocking arm 52 extending from cradle 53 is adapted during the normal position to be held above the extremity of disengagement lever 23 which operates upon clutch 21 of record reader shaft 18 to disconnect driving engagement between the driving and driven members thereof.

As soon as operating handle 105 is started into oscillation either manually or through the control unit then finger 51 is raised out of engagement with extension 134 permitting cradle 53 to respond to the urge of its spring 135 and assume a position whereat blocking arm 52 is presented behind disengagement lever 23.

The performance of cradle 53 under control of finger 51 constitutes a secondary interlocking mechanism, the initial one being the latch bar 33 and its associated elements 34 and 44. Finger lever 126 responds as follows:

With the elevator shaft started into rotation cam 27 engages roller 107 urging it into the position indicated in Fig. 4. Assuming that the movement of the elevator is blocked, shaft 98 resists the motion thus imparted to it by auxiliary portion 106 through segment 109 and roller 113 and instead of yielding there to the force transmitted through auxiliary member 106 engages roller 113 of plunger 114 compressing spring 115 within handle 105. It will be noted that the operative connection between cam shaft 17 and elevator shaft 98 is at no time broken nor discontinued but that a continued application of power subsists throughout the entire cycle of operation and that the power source and actuating mechanism is at all times in readiness to function should the impediment be overcome or the interfering irregularity be adjusted.

Where the interference with the movement of shaft 98 is effective from the initial rotation thereof, finger lever 126 being secured to and rotatable with auxiliary member 106 describes a full angular motion until detent member 132 becomes disengaged entirely from openings 129 and 131 and instead enters another opening 136 in segment 128 so that on the completion of rotation of shaft 17 finger lever 126 will remain in a position as indicated in dotted lines in Fig. 3 through the engagement of detent 132 with orifice 136 though crank arm 106 follows cam 27 back to normal position. Where, however, in-

stead of interfering with the motion of shaft 98 from the start, an impediment is encountered in the final portion of its angular movement only, detent member 132 merely rides out of engagement with the lower opening 129 of the two intersecting openings and rides into engagement with the other 131. In either event, finger lever 126 is restrained from returning to its normal position with the detent 132 in registration with opening 129, and though the auxiliary member 106 is permitted to resume its normal position, finger 51 will, nevertheless, fail to engage extension 134 of cradle 53 without which blocking arm 52 remains in its effective position holding disengagement lever 23 against driven portion of clutch 21 and preventing its reengagement. In this manner the interference which prevented the normal operation of elevator shaft 98 operates to prevent the further performance of the record reader 25 until an attendant manually restores the mechanism into operative condition, which he does by engaging thumb piece 133 of finger lever 126 urging it back to its normal position. It will be understood that before so doing the attendant will first have remedied the cause for the interference with the normal movement of the elevator mechanism.

Modifications

In the modified form of the rail shift mechanism illustrated in Figs. 9 to 13 inclusive, provision is made whereby in addition to the advantages obtained by the practice of the preferred form described above an additional advantage is had in enabling the mixed assembling of matrices in any desired combination, that is, the incoming matrices are set at the respective levels individually. In accordance with this practice, as best illustrated in Figs. 9 and 12, a longitudinally shiftable rail 137 is provided with a spring element 138 for normally urging it leftwardly.

Rail 137 at its inner surface which serves as a support to incoming matrices, terminates with an extended portion 139 having an upturned projection which when the rail 137 is in its normal position is presented as shown in Fig. 12, but during the shifted position of rail 137 projection 139 is presented as indicated in Fig. 13. Accordingly, in either of its positions projection 139 serves to positively hold those matrices that have already been selectively received while also to more definitely determine the position in which subsequently released matrices are received.

As will be seen in Figs. 12 and 13 the structure of the assembling block is preferably made to accommodate the requirements of the improved rail 137. The ingress portion of the block 75 is beveled as at 140 affording a flared entrance to the matrices as they descend so that in case a matrix in dropping should happen not to be properly aligned the flared ingress surface 140 acting as a diminutive hopper serves to realign it. In order to further assist in the reception of matrices it has also been found expedient to provide the foremost portion 150' of the block 75 as a floating part being held in position solely by a flat spring 150 which is secured to it and also to the main portion of the block 75. By reason of the extensive length of spring 150 between the points at which it is secured it permits not only of vertical flexibility and movement on the part of portion 150' but also of some horizontal motion as well thereby allowing

member 150' a certain amount of deflection in the event it is struck by a descending matrix that is out of alignment.

The forward edge of the rail 137 is beveled as 5 may be seen in Fig. 13 and the adjacent corner of floating portion 150' is also thus beveled. This is so provided in order that rail 137 shifting into its position as illustrated in this figure, may 10 cam member 150' upwardly and be permitted to lie completely beneath it. This practice of providing a displaceable ingress portion permits the rail 137 to have its full width throughout excepting the small extension 138 which otherwise would have to be considerably longer and consequently 15 that much weaker and less able to withstand the strain of buffing the matrices upon their descent.

An extension 139 preferably formed integrally with rail 137, Fig. 9, is engaged by one arm 141 20 of a bellcrank member 144 pivoted at 142. The other arm 143 of bellcrank member 144 is pivotally connected to a link 145 which has an expandable yielding construction 146 intermediate thereof and is pivotally connected to one arm 147 25 of a T-shaped lever 148 pivoted at 149. Each of two other arms 151 of T-lever 148 is connected to one of a pair of parallel bars 152 which are joined parallelogrammatically with a release lever 153 pivoted to the elevator arm 97 at 154. 30 The extremities 155 of parallel bars 152 extend slightly beyond release lever 153 and are each adapted to be engaged by a depending portion 156 of each of a pair of first class levers 157, as best indicated in Fig. 11.

35 Levers 157 are substantially similar in shape and are carried on a common vertical pivot shaft 158. The end of each lever opposite the one that engages the extremity 155 of its parallel bar 152 is presented to be engaged by a lug 159 carried by each of a pair of adjacent selectable elements 161 and 162 which are under control of permutation bars 53 similar to the general class of selectable elements 61.

Upon the selection of either of the elements 45 161 or 162 the lug 159 thereof engages its lever 157 thrusting the opposite end against its associated parallel bar 152 and rotating T-lever 148 in accordance therewith, while the other of the two parallel bars is simultaneously restored 50 to its non-operating position by reason of its articulation to T-lever 148 as may be readily seen in Fig. 10. Thus, it will be understood that a special signal which selects one of the elements 161 or 162 will cause the presentation of shiftable rail 137 into one position while the selection of the other of the elements in response to another special signal will cause the presentation of shiftable rail 137 into the other of its positions.

60 General operation

In the absence of any interference with the operation of the elevator mechanism the unit 65 will respond as follows: The control form 54 is fed intermittently through the receiving die 55 of the record reader mechanism 25 where during the rest period intervening each such motion, the code combination of the transverse row of perforations is simultaneously sensed by the set 70 of feeler levers 56. Thereafter this code combination is transferred to the code bars 58 by the transfer levers 57 causing to be presented an alignment of notches 29 opposite one of the selectable elements 61. In timed relation to the 75 setting of the code bars 58 cam shaft 65 is ro-

tated clockwise as viewed in Fig. 6 until its apices no longer spread the elements 61 whereupon the particular one opposite the aforementioned alignment of notches is permitted to assume its selected position, as illustrated in dotted lines in this figure. Following this, common actuator bar 63 receives a measured stroke which by the interposition of the foremost portion of the selected elements 61 imparts said motion to the corresponding yieldable member 67, in the 10 case where the particular selection pertains to a matrix signal. Where, however, the particular selection does not pertain to the release of a matrix but instead relates to a preparatory function such as for example the shifting of 15 the duplex rail 78 of the assembling block 75 the forward movement of selected element does not engage a yieldable member 67 but instead, by its lug such as 159, causes the actuation of the particular function mechanism associated 20 therewith.

Where the particular selection pertains to the operation of the elevator mechanism it causes a selective operation of bar 31, Fig. 3, rotating T-lever 34 counterclockwise and latching bar 38 25 behind shoulder 41 of latch lever 42 and arresting record reader shaft 16 by presenting disengagement lever 23 in its effective position. Through its articulation with floating lever 45 the rightward movement of latch bar 38 causes 30 the engagement of the intermediate portion thereof with bellcrank member 46 thereby rotating it counterclockwise and withdrawing its blocking portion 48 from behind elevator clutch disengagement lever 24. Thereafter shaft 17 is 35 permitted to rotate one complete revolution and is again arrested by the action of disengagement lever 24 under control of a single revolution clutch mechanism completely disclosed in the copending application. During its revolution 40 shaft 17 through the instrumentality of cam 27 raises the auxiliary arm 106 to the position indicated in Fig. 4 and thereafter allows it to return to its normal position as indicated in solid lines in Fig. 3. During the cycle of rotation cam 49 also carried by shaft 17 releases 45 latch lever 42 permitting latch bar 38 under influence of spring 36 to override the shoulder 41 and restore to normal position the T-lever 34 and its associated elements.

The restorative motion of T-lever 34 permits disengagement lever 23 of the record reader shaft clutch 21 to respond to its spring (not shown) and assume its ineffective position provided, however, that blocking arm 52 of cradle 53 is also in its ineffective position. Where, however, the free and complete movement of the elevator shaft 98 is interfered with finger lever 126 becomes dislodged from its normal position against the tendencies of detent 132 in holding 60 it thereat and upon the return of the auxiliary arm 106 finger 51 of lever 126 fails to reengage the extension 134 of cradle 53 permitting the latter, through its arm 52 to continue to block the release movement of disengagement lever 23. 65

The restoration to normalcy of the mechanism, after it has been blocked by interference from movement of the elevator, is a manual adjustment as described above.

While the foregoing description has been 70 drawn to a particular disclosure it will be understood that numerous modifications and variations may be made without departing from the scope of the present invention. It is therefore intended not to be limited to the foregoing de- 75

scription, nor the disclosure in the accompanying drawings but rather to include all matter as may be construed in accordance with the following claims.

5. What is claimed is:

1. In a linecasting machine, a matrix conveying mechanism, an automatic control mechanism, a source of mechanical power for operating said conveying mechanism in response to 10 said control mechanism including a periodically operated power shaft, a conveying mechanism operating shaft, a handle for manually operating said last mentioned shaft, and a resilient connection contained within said handle for associating said power shaft to said conveying mechanism shaft and automatically rendered ineffective in the event of predetermined resistance to movement by said conveying mechanism shaft.

2. In combination with a linecasting and composing machine, a control unit including a periodically driven shaft, a conveyor mechanism, manual control means for operating said conveyor mechanism including a handle secured thereto, and a yielding element contained within 25 said handle constituting an operative connection between said shaft and said mechanism which element yields under predetermined resistance for absorbing the driving power.

3. In a linecasting machine, a conveyor, a shaft positively connected to said conveyor for operating it thereby, a crank arm carried by said shaft, an automatic control unit including a power driven shaft, a cam carried by said power shaft operable upon said crank arm for oscillating said operating shaft, and means for storing the force imparted by said cam under control of predetermined resisting forces.

4. In a linecasting and composing machine, an automatic control unit including a periodically operating power shaft, a mechanism to be operated by said power shaft, and a connection between said shaft and said mechanism including a compression spring yieldable in a direction transverse to that of said connection and continuously urging the movement of said mechanism.

5. In a linecasting and composing machine, an automatic control unit including a plurality of individually selectable elements, a receptacle for receiving assembled matrices including a shiftable rail for supporting said matrices, means directly operative by one of said elements for moving said rail into one condition of operation, and a spring detent responsive to a predetermined condition of said receptacle for maintaining said rail in the other condition of operation.

6. In a linecasting and composing machine an automatic control unit including a plurality of elements individually movable into selected position, a movable receptacle for receiving assembled matrices including a rail shiftable into effective and ineffective positions, a lever movable with said receptacle for shifting said rail into each of said positions responsive to the selective movement of one of said elements for moving it into one position and that another of said elements for moving it into the other of said positions.

7. The combination set forth in claim 6 in which each of said elements is provided with means which during its operation restores the other of said elements to normal position.

8. In a linecasting and composing machine, a carriage for receiving assembled matrices, an

arm for bodily lifting said carriage during periodic cycles of operation, a rail associated with said carriage for selectively supporting assembled matrices, mechanism carried by said arm for alternatively positioning said rail, and an automatic control unit including a pair of individually selectable elements each operative to actuate said mechanism into one of its alternative conditions of operation.

9. In a linecasting machine, a holder upon 10 which matrices are assembled, a lower matrix support for said holder, an upper matrix support for said holder capable of selective withdrawal, a conveyor for transporting said holder, conveyor raising mechanism, shifting means for 15 said upper support carried by said conveyor raising mechanism, and automatically controlled means for operating said shifting means.

10. In a linecasting and composing machine, a control unit including a central operating 20 mechanism, a record reader responsive to perforations in a tape for setting up element selective conditions, a plurality of individually selectable elements receiving operative motion from said mechanism and individual selective clearance from said record reader, an assembling carriage including a supporting rail alternatively shiftable into different positions, and means receiving motion transmitted from certain of said elements directly for selectively 30 shifting said rail.

11. In a linecasting and composing machine, a matrix assembling block including a main member affording a trackway into which are received an alignment of matrices in assembling 35 operation, a floating ingress portion on said block, and a resilient securing member for holding said ingress portion in position on said block universally yieldable to permit said portion a limited freedom of movement in accommodat- 40 ing incoming matrices.

12. In a linecasting and composing machine, a matrix assembling block including a lower rail for supporting received matrices at one level, a shiftable upper rail for supporting received 45 matrices at another level including a main member affording a slot into which said shiftable rail is adapted to reside, a portion on said rail extended foremost therefrom so as to be disposed at a proper point for engagement with 50 incoming matrices, and a foremost portion on said main member for aligning incoming matrices upon their reception but yieldably connected to said main member so as to be displaced thereat to permit the subjacent position- 55 ment of said shiftable rail thereunder.

13. In a line composing machine, a matrix conveyor, a shaft rotatable for operating said conveyor, a power driven mechanism including a periodically operative cam, an arm associated with said shaft for receiving motion from said cam, a resilient element connecting said arm and said shaft, and means associated with said element for varying the stiffness thereof.

14. In a line composing machine, a periodically operated apparatus, automatic means initiated by signals for operating said apparatus including a driving shaft capable of imparting a motivating impulse, a driven shaft for receiving said impulse and delivering it to said apparatus, and a resilient connecting means intermediate said shafts capable of absorbing said impulse in the event of undue resistance to movement on the part of said driven shaft 70 75

and releasing it as soon as such resistance is overcome.

15. In a linecasting and composing machine, an elevator, a matrix receiving block carried by said elevator, a shiftable rail for selectively supporting or rejecting incoming matrices, a spring for urging said rail into one position, a detent for holding said rail in the other position against the tendencies of said spring, and a signal controlled mechanism for releasing said detent in response to certain signals.

16. In a linecasting and composing machine, a signal responsive control apparatus for initiating the functions of said machine, a conveying mechanism, a motive source under control of said apparatus for operating said conveying mechanism including a rotatable shaft, and a resilient connecting means between said shaft and said source capable of absorbing the driving power of said source under predetermined conditions and tending to restore normal conditions reactively.

17. In a linecasting and composing machine, a control unit for automatically initiating the functions of said machine, a conveyor, a shaft positively connected to said conveyor for operating it thereby, a crank arm carried by said shaft, a power driven shaft under control of said unit, a cam carried by said power driven shaft operable upon said crank arm for oscillating said operating shaft, and means for storing the force imparted by said cam in the event of predetermined resisting forces.

18. In a linecasting machine, a matrix conveying mechanism, an automatic control mechanism for releasing matrices to said conveying mechanism, a source of mechanical power for operating said conveying mechanism in response to said control mechanism, including a periodically operated element, means through which said conveying mechanism is actuated, a handle for manually operating said means to lift said conveying mechanism, and a resilient connection contained within said handle through which power is communicated from said element to said means and rendered ineffective automatically in the event of predetermined resistance to movement of said conveying mechanism.

19. In a linecasting and composing machine, a periodically operated organ, a source of motor power for actuating said organ including a driven shaft, a driving shaft, a yieldable element associated with one of said shafts, and a cam member associated with the other of said shafts for imparting driving power through said yieldable element having a component which may be varied in accordance with the angular slope or rise of said cam.

20. In a linecasting and composing machine, a periodically operated conveyor mechanism, a signal responsive control unit including a source of motor power for actuating said conveyor mechanism, a driven shaft for operating said conveyor mechanism, a driving shaft associated with said driven shaft, and a coupling apparatus between said driven and driving shafts including an element associated with one of said shafts having a yieldable plunger, a cam associated with the other of said shafts cooperating with said plunger for imparting driving power therethrough between said shafts, the rise in the surface of said cam affording a component

force which may vary with respect to the resiliency of said yieldable element.

21. In a linecasting and composing machine, a periodically operated conveyor mechanism, a signal responsive control unit including a source of motor power for actuating said conveyor mechanism, a driven shaft for operating said conveyor mechanism, a driving shaft associated with said driven shaft, and a coupling apparatus between said driven and driving shafts including a member secured to one of said shafts and extending transversely to the direct line in which power is to be communicated to said shaft, a yieldable plunger within said member, and a cam associated with the other of said shafts in cooperative relation with said plunger for affording a component yielding relationship between said driving and said driven shafts in accordance with the angular surface of said cam with respect to said plunger.

22. In a linecasting machine, a periodically operated organ, an automatic control apparatus responsive to certain stored signals for initiating into operation said organ comprising a driving shaft, an operating cam carried by said shaft, a driven shaft, an arm secured to said driven shaft, and means for communicating the power from said cam to said driven shaft comprising a secondary arm loosely carried by said driven shaft and a yieldable connection between said secured arm and said loosely carried arm.

23. In a linecasting machine, a matrix conveying mechanism, an automatic control mechanism, a source of power for operating said conveying mechanism in response to said control mechanism including a periodically operated power shaft, a conveying mechanism operating shaft, a handle secured to said conveying mechanism operating shaft for manually actuating it thereby, a resilient connection contained within said handle, and a rotatable cam cooperating with said resilient connection for associating said power shaft to said conveying mechanism shaft, said connection automatically rendered ineffective in the event of predetermined resistance to movement by said conveying mechanism shaft.

24. In combination with a linecasting and a composing machine, a control unit including a periodically driven shaft, a conveyor mechanism, 50 manual control means for operating said conveyor mechanism comprising a handle secured thereto, a yieldable element contained within said handle, and a cam cooperating with said yieldable element and constituting an operative 55 connection therewith between said shaft and said mechanism collapsible under predetermined resistance for absorbing within said yieldable element the driving power communicated by said cam.

25. In a linecasting and composing machine, an automatic control unit including a periodically operating power shaft, a mechanism to be operated by said shaft, and a connection between said shaft and said mechanism including a cam 65 and a spring-pressed follower yieldable in a direction transverse to the force communicated by said power shaft and continuously urging the movement of said mechanism.
